Inventor

By his Attorney Edwin Leisohn

UNITED STATES PATENT OFFICE.

BENJAMIN GROSS, OF NEW YORK, N. Y., ASSIGNOR TO BENJAMIN GROSS COMPANY, INC., OF NEW YORK, N. Y., A CORPORATION OF NEW YORK.

DESIGN FOR A FINGER RING OR ARTICLE OF SIMILAR NATURE.

Application filed May 10, 1923. Serial No. 6,125. Term of patent 3½ years.

To all whom it may concern:

Be it known that I, BENJAMIN GROSS, a citizen of the United States, residing at New York city, in the county and State of New York, have invented a new, original, and ornamental Design for Finger Rings or Articles of Similar Nature, of which the following is a specification, reference being had to the accompanying drawing, forming a part thereof.

I claim—

The ornamental design for a finger ring or article of similar nature as shown.

BENJAMIN GROSS.
